BUILDING CONSTRUCTION

Bernard London, New York, N. Y.

Application March 5, 1938, Serial No. 194,052

13 Claims.

(Cl. 72—16)

This invention relates to building construction.

This application is a continuation in part of my application Serial No. 23,369, entitled "Building construction", filed May 25, 1935.

One of the objects of this invention is to provide a building construction, particularly a wall or ceiling-floor construction, or the like, adapted to form a boundary of a room, space or building, that will be inexpensive in construction, capable of rapid erection and ease of assembly and adapted to meet a widely varying range of usefulness. Another object is to provide a wall construction in which parts of rapid and inexpensive fabrication may be employed. Another object is to provide such a construction in which sheet metal of economic cross-sections or shapes may be utilized. Another object is to provide such a construction in which a wide variety of available building materials, such as lathing, plaster, concrete, heat-insulating mediums, sheet materials like plaster-board, fiber-board, sheet-rock, and other prefabricated or built-up or natural sheet materials may be economically and practicably utilized.

Another object is to provide a construction of the above-mentioned character which is readily adaptable for use in various parts of a building construction, such as an outside wall, an inside wall, partition walls, ceilings, flooring, roofing, or the like. Another object is to provide a construction in which the parts may be readily and inexpensively prefabricated, particularly on a large scale, and thus to bring down the cost, and in which the parts are capable of rapid assembly or installation; another object is to carry out this last-mentioned object in a way which will permit a wide choice or range of selection of materials. Another object is to provide a construction of the above-mentioned character that is well suited or adaptable to modern methods of heating, cooling, or conditioning. Other objects will be in part obvious or in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawings in which are shown several of the various possible embodiments of the mechanical features of my invention,

Figure 1 is a cross-sectional view through a wall;

Figure 1^a is a perspective view of a spacing and reinforcing element employed in the construction of Figure 1;

Figures 2, 3, 4 and 5 are cross-sectional views of illustrative modifications or embodiments of my wall construction.

Similar reference characters refer to similar parts throughout the several views in the drawings.

Referring first to Figures 1 and 1^a, I have there shown certain features of construction disclosed in my above-mentioned co-pending application Serial No. 23,369; it comprises a plurality of spacer and reinforcing members 10, preferably made up of sheet metal and illustratively taking the form shown in Figure 1^a, being of any convenient length and, where the wall is to be a vertical wall, the members 10 may be of a length commensurate with the height of one story or the spacing from floor to ceiling. As is better shown in Figure 1^a, the members 10 are preferably made of sheet metal of suitable weight.

Each member 10 comprises a central strip-like portion 11 preferably imperforate throughout its length and preferably stamped or formed as at 12, preferably along its median or center line, to bulge it out of the plane of the central portion 11 and thereby giving it a rib or channel-like section to render the member 10 sufficiently strong to resist bending and to function where desired as a column.

At appropriate intervals along its length the member 10 is cut or slit transversely and the resultant pairs of strap-like members are bent alternately in opposite directions out of the plane of the central portion 11. Thereby, there are formed pairs 13—14 of arms directed to one side of the plane of the portion 11 and pairs of arms 15—16 extending to the other side of the plane of the portion 11.

These various arms, furthermore, preferably extend at such angles to the plane of the central portion 11 that, when the members 10 are assembled in the wall structure, the aligned arms 14—16 of one member 10 form an angle whose apex or channel is indicated at A¹, while arms 13—15, also respectively aligned, form an angle whose apex or trough-like angle is indicated at A², the one facing toward the other, and all of them extending along a plane intermediate of the two spaced planes in which fall the ends of the respective pairs of arms, all for a preferred purpose later described.

The opposed pairs of arms are adapted to have connected thereto suitable structural elements or

building materials and by way of illustration and as disclosed in my above-mentioned co-pending application, the latter may take the form of sheet members 17-18 which may be of materials like those disclosed in my above-mentioned application. They may be secured to or interlocked with the arms of the members 10, the latter being appropriately spaced, in any suitable manner and illustratively the various arms above-mentioned 5 may be bent adjacent their extreme end portions, as at 19, appropriately inclined to the respective arms and spaced apart to substantially mate with the angles and spacing of the inclined vertical edge faces of dovetail members 20 which are secured or otherwise related in any suitable manner to the members 17 and 18 and which are spaced therealong commensurately with the spacing of the column-like spacer or core members 10, these dovetail members being interengaged with the respective vertically aligned spaced arms and thereby the members 10, 17 and 18 are mechanically and securely held together and with the members 17 and 18, where they take the form of prefabricated sheet material, held in accurate parallelism and alinement with each other. 10 All of the above is disclosed in my aforesaid pending application.

According to certain features of my present invention, I provide sheet members 21 of appropriate material, illustratively sheet metal, and preferably of a length commensurate with the length of the members 10, but of a width preferably slightly in excess of the spacing between the apexes A¹, A² into which the respective vertical edges of the sheet members 21 are received and shown in Figure 1, each member 21 being preferably somewhat bowed or arched, particularly where the wall is to be an outside wall, the arching being preferably in a direction toward 15 the outside.

Thereby, the sheet members 21 alternated with the central column-like portions 11-12 form a continuous diaphragm or barrier-like means extending between the outer and inner 20 wall surfacings and preferably adjacent the median or central plane therebetween; thereby there are formed a preferably continuous or uninterrupted space OS to one side of this diaphragm or barrier means 21-11 and a similar 25 space IS on the other side thereof.

Where the wall is to form an outside wall the space OS may be filled with any suitable material indicated at M and that material may take the form of concrete which, upon setting, interlocks with the parts it contacts with, including the arms 15-16 and the dovetail members 20, or that material may take the form of a heat-insulating medium like rock wool, mica pellets, or the like, or any other suitable or appropriate material. The space IS is preferably left free, particularly where, according to other features of my invention, it is desirable to utilize the space, as is better set forth in my co-pending application Serial No. 194,051, filed of even date herein 30 with, for the handling of a cooling or heating medium, such as air, in which case the wall surfacing 17 is preferably of good heat conducting characteristics, for thereby I may circulate through the space IS hot air in the winter or 35 cooled air in the summer, thereby maintaining such a temperature difference between the space IS and the room space that heat flows into the latter in winter and out of the latter in the summer. Or the space IS may be utilized as a duct 40 for the passage of such heating medium to the

space or other parts of the building, and where the room or building space is to be air conditioned, thus to take care not only of temperature but also humidity and also dehumidification, the space IS may be utilized, appropriate openings, registered, or the like, being provided in the wall surfacing 17 for communication with the room or building interior. Or the space IS may remain sealed to form a dead air space, having also insulating properties. Under some circumstances I may also wish to line the sheet members 21 with or form them of a heat-insulating material; an illustrative lining is indicated at 45 22 and may comprise any suitable material, such as sheet fiber-board, asbestos composition, or the like, and similar linings may be provided for the column portions 11, as indicated at 23. This is preferably where the material M takes the form of concrete. Where the wall structure is to function as an inside or partition wall, either or 50 both spaces OS and IS may be left void and the intervening sheet members 21 omitted, if desired, or either or both of said spaces may be filled with the material M which in such case 55 preferably takes the form of any suitable sound insulating material or medium. It is to be understood, however, that the parts 17 and 18 of Figure 1, in carrying out my present invention, may take any suitable or appropriate form; thus, the part 18, where it is to be the external wall 60 surfacing, may take the form of tile, brick, stucco, or any other appropriate material, and the part 17 may take the form of any suitable material to constitute an appropriate inside wall surfacing where it is to function as such, including lathing 65 and plaster, all as described in my co-pending application filed of even date herewith.

The above-described features of my present invention may, as already indicated, be carried out in various other forms, several of which are, by 70 way of illustration, shown in Figures 2-5. Thus, turning to Figure 2, the outside wall surfacing is indicated at 18 and the inside wall surfacing at 17 and spaced appropriately therebetween are sheet metal column members generally indicated by the reference character C, 75 preferably made up of sheet metal and provided with appropriate end flanges 27-28 to give them a substantially channel-like cross-section for column action and resistance against bending. The main webs 29 thereof are rolled or bent to 80 form two adjacent ribs 30 and 31, thus increasing the rigidity but also providing in each column member C a vertically extending channel A¹ opening to one side of the web 29 and another channel A² opening to the other side of the web 29. Thus, two successive column-like core and spacer elements C present toward each other two channels A¹-A² into which are received the opposed edges of the sheet member 21 in the 85 manner described above in connection with Figure 1, the member 21 being of heat insulation material or lined with a sheet of the latter, as at 22. Thus, the sheet members 21 in coaction with the ribbed intermediate portions of the members 90 C form a continuous intermediate diaphragm or barrier portion providing again two spaces OS and IS which may be utilized and treated as above described in reference to Figure 1.

Where the parts 17-18 are of prefabricated or 95 prepared sheet materials or members, the wall may be made up of completed sections or units comprising, as is the case with Figure 1, inner and outer sheet members 17-18 and intermediate core and spacer members connected thereto, 100

with the diaphragm sheet members 21 horizontally interposed between the latter; the dovetail connections 19-20 of Figure 1 facilitate assembly of the parts to make up such a wall unit or section, while with the construction of Figure 2 the flanges 27-28 are utilized to secure the sheet members 17-18 thereto in any suitable manner.

According to other features of my invention, however, I provide for a rapid and speedy edge to edge interconnection of such units which may be of any appropriate size suitable for economic fabrication and speedy and economic installation. Thus, a unit may be three or four feet wide and where it is to form a vertical wall may be of a length about the same as the floor to ceiling dimension. For interconnecting adjacent units, the left-hand end column and spacer member C of one unit has its flanges 27 and 28 flanged over as at 33-34, substantially at an acute angle to the plane of the flanges 27-28, respectively, forming thus a ratchet-like cam or hook member. The right-hand end column spacer member of the adjacent unit has its flanges 27-28 bent into the hook-like shapes shown at 35 and 36 in Figure 2. Accordingly, in assembling adjacent units, they are simply forced edge to edge, the hook-shaped parts 35-36 successively or simultaneously flexing or yielding under the camming action of the parts 33-34, respectively, ultimately snapping over the latter under the springiness of the sheet metal employed, and thus securely alining and connecting together adjacent units. If desired, and during this same action, a sheet member 21^a may be seated in the vertical channels A²-A², preferably by seating it first into one, its other edge entering into the other in process of assembly.

As above indicated, the sheet members 17-18 may be secured in any suitable way to the flanges 27 and 28; where one or both of the parts 17-18 is of metal or wire lathing, spot welding may be employed to secure it to these flanges, and likewise where either or both of the members 17-18 are of sheet metal. The column core members C may also be of sufficiently light sheet metal to permit members 17-18, or either of them, to be wire stitched or stapled thereto, or other means may be employed.

Where it is desired that either space OS or IS be continuous throughout the extent of the wall, that is, not interrupted by the sheet metal of the spacer column members C, the webs 29 may be suitably apertured, as indicated at 37.

In the event that relatively very heavy column members, such as the lighter weight of structural steel channels, are to be employed, as indicated at D in Figure 3, thus not lending themselves so readily to embodiment in the form above described in Figure 2, for effecting interconnection or for formation to receive the diaphragm sheet members 21, I may proceed as shown in Figure 3, providing the webs 40 with longitudinally extending sheet metal members 41, one on each side and secured thereto as by spot welding, these members 41 being preferably of a length the same as the length of the webs D and being bent up or channeled as shown, thus again to provide in adjacent core columns vertically extending channels A¹ and A² facing toward each other for the reception of the sheet member 21 which, if made of sheet metal, may have associated with it a sheet member 22 of a heat insulating medium, likewise received in the channels A¹-A².

In assembling the wall part 18 to the members D where the former take the form of sheet

members, I may secure to them in any suitable manner sheet metal strips 43 extending vertically and shaped as shown to provide a flange portion 44 spaced from the inside plane of the member 18. At the right-hand end, however, of each sheet 18 and on the inside face thereof, I provide a similar metal strip 43 with a spaced flange part 44, but it is secured so as to face toward the right instead of toward the left. To the end web 45 of the members D I secure elongated sheet metal members 46, preferably bent or flanged around the web 45 and secured as by spot welding, and dimensioned to be snugly received in the space between the inside face of the member 18 and the flange 44 of the securing member 43, but the member 46 has an inwardly bent extension 46^a over which engages the part 44 that faces to the right, of the next to the last sheet member 18. Preferably, the interengagement of these parts is substantially permanent like the interlocking of the parts 33 and 35 of Figure 2; for that purpose the inside flange extension 46^b terminates short of the web 40 of the member D while the flange part 44 is beaded or bent over, as at 44^a, to take over the end edge of the part 46^b, the springiness of the part 44 to take place to snap or spring the hook-like part 44^a over the abutment-like edge of the part 46^b. In similar way, the part 46^a is sharply flanged as at 46^b to form a hook-like part over which the flange or hook part 44^a of the part 44 snaps. Thus the parts are dependably interlocked. The members 43 may be made up of such material or weight of sheet metal to facilitate the use of any suitable or desired method of securing them to the sheet members 18.

The opposite end webs 48 of the channel-shaped members D may have the wall portion 17 secured thereto in any suitable way and where the portion 17 takes the form of certain kinds of sheet material, I may relate to the web 48 longitudinally extending sheet metal members 49, shaped as shown in Figure 3, and bent up to provide a recess or seat 49^a to receive the edge of the web 48 which is held therein by the spring action of the part 49 due to the tensioning thereof by having the portion 49^b thereof strained or stressed against the left-hand face of the web 40, the sheet metal parts 49 providing longitudinally extending channels 49^c and 49^d in opposed pairs of which the sheet members 17 are edgewise received, being, if desired, initially bowed and hence sprung into position.

The spaces OS and IS of the structure of Figure 3 may, of course, be treated as was above described in connection with Figure 1.

Under certain circumstances it may be found desirable to construct the wall or like section in a manner like that shown in Figure 4, particularly where sheet form of building materials can be or are desired to be utilized. For purposes of illustration, let the part 18 of Figure 4 represent one such sheet member and the part 17 the other, intended to form the, or parts of, inside or outside wall surfacings. With the arrangement of Figure 4, the two opposed sheet members 17 and 18 are, when assembled, preferably staggered so as to bring the junction indicated at J¹ between adjacent edges of two sheet members 18 opposite an intermediate portion of an opposed sheet member 17, and to bring the junction indicated at J² between two adjacent sheet members 17 opposite an intermediate part 75

or portion of an opposed sheet member 18. The contiguous faces of the sheet members 17 and 18 are provided with or have secured thereto in any suitable manner, as by wire stitching or 5 stapling, indicated generally at S, spacing and securing core-like parts which are preferably of sheet metal which may be relatively light and which preferably has some springiness or is given an appropriate resiliency at appropriate parts 10 by suitably conforming it. These sheet metal parts may be of any desirable extent or length and preferably and illustratively they are of a length commensurate with that dimension of the sheet members along which they extend. 15 These metal members preferably have the same coactions but preferably and to achieve certain advantages later mentioned, are made up in three specifically different forms indicated, respectively, by the reference characters E, F and G. 20 Thus, suitably spaced and extending lengthwise of one of the sheets, like sheet 18, and intermediate the longitudinal edges thereof, is a suitable number of members G; each member G is of sheet metal formed or rolled to provide 25 two preferably parallel parts 50, 51, flanged as at 52, 53, the latter resting flat against the sheet 18 and secured thereto in any suitable way. The intermediate portion of member G and which joins the parts 50—51 is rolled or formed to 30 give it the shape shown whereby there is a longitudinally extending channel 54 approximating a circular cross-section but having a neck portion 55 that is narrower than the inside width of the channel portion 54; the sheet metal is 35 shaped to form a trough-like entry to the neck portion 55, as by rounding the sheet metal as at 56 and 57, gradually merging it into the parts 50—51 but at the junction thereof providing in each part a longitudinal groove or channel, as 40 at A² in the part 50 and A¹ in the part 51. Because of the conformation of the sheet metal, the narrow neck portion 55 is springy and may yield resiliently in the direction of widening it. 45 The member F is positioned along that portion of the sheet member 18 opposite to which the junction J² is to come and it is constructed like the member G above described being provided with three yieldable channels or recesses 54^a, 54^b and 54^c. 50 The sheet member 17 has secured to it a member F and it extends lengthwise thereof but opposite to the place where the junction J¹ between two opposed sheets 18, 18 is to come, and opposite the members G, G on sheet member 18, the 55 member 17 is provided with members E, E, also of sheet metal and constructed generally like the members G excepting that, instead of being formed to provide a longitudinally extending recess 54 with a narrow neck, the sheet metal is 60 formed to provide a longitudinally extending head 58 preferably somewhat wedge-shaped so that it can wedge itself through the narrow neck 55 by causing the walls thereof to yield, as above-mentioned, whence it is narrowed in cross-section, as at 58^a and preferably also shaped to conform to the curvatures of the parts 56—57 which thereby preferably interfit therewith and yieldably but securely grip the head-like part 58. At 65 the adjacent end portions of the sheets 17, 17 and 18, 18 are secured and mounted the members E¹; they are substantially similar in construction to the members E excepting that one of the flanges thereof, namely, flange 59, is shaped 70 as shown in Figure 4 to form a longitudinally

extending seat to receive the end or edge portion of the sheet member.

The component parts of the wall structure may thus be prefabricated and the sheet members 17 and 18 provided with the core and connecting 5 members E, F, G and E¹. Arrived on the job, the wall structure may be assembled in a manner that will now be clear, by forcing opposed sheet members flatwise toward each other to cause each head-like member 58 of a part E to be 10 forced and sprung into the recess 54 of an opposed member G, but the longitudinally extending head portion 58 of one part E¹ becomes seated in the resilient channel 54^a of a member F, thus anchoring the end portion of one sheet 15 to an intermediate portion of the opposite sheet, while the end portion of the next adjacent sheet member, also provided with a member E¹, has its headed part 58 forced into the resilient channel 54^c of the same part F, thus anchoring that end of the adjacent sheet E to an intermediate portion of the opposite sheet member. 20

By the structure just described, the various sheet metal members will be seen to provide pairs 25 of longitudinally extending channels A¹ and A² into which may be received the opposed edges of sheet members 21 which may or may not have associated with them sheet insulating material 22. The members 21 with the column-like sheet 30 metal core and connector elements again divide the space between the spaced sheets 17—18 into an outer space OS and an inner space IS, and if these spaces are desired to be unbroken by the parts 50—51 of the members E, F, G and E¹, the 35 latter may be apertured at appropriate intervals and either or both of the spaces OS and IS may be treated in the manner above-described in detail in connection with the previous figures.

Certain of the advantages of the construction 40 of Figure 4 may be achieved by appropriately modifying the construction of Figure 2 above described, as indicated in Figure 5 where the members C of Figure 2 are shown but made up in two parts C¹ and C², as if the webs 29 of the parts C of Figure 2 were cut in two throughout their length but to one side of the ribbed parts 30 and 31 which not only strengthen the members but also provide the diaphragm or barrier-receiving channels A²—A¹. Preferably, in Figure 50 45 50, the two parts C¹ and C² are made up separately, as by rolling and forming out of suitably heavy sheet metal, but the webs of the two parts are provided with bent flanges shaped the same and given the same designations as the parts 33 and 35 of Figure 2. 55

Accordingly, one half portion of the wall structure, comprising the sheet material 18 with the parts C¹ secured thereto may be set up and the sheet members 21 related edgewise to the opposed channel recesses A¹—A² whence the sheet material 17 with the members C² secured thereto and spaced commensurately with the spacing of the members C¹ may be set and forced flatwise toward the sheet material 18, the parts 33 60 65 camming the hook-shaped parts 35 into interlocking relationship with each other, thus completing the assembly of the wall structure.

Thus, again, two spaces OS and IS are provided by the action of the barrier or diaphragm 70 parts 21 etc., just as in Figure 2, and either or both of these spaces may be treated in the manner described above in connection with Figure 1.

Where the above-described structures are to function as vertical walls, the various column- 75

like members, such as the members 10 of Figure 1, the members C of Figure 2, the members D of Figure 3, the members E, F, G and E¹ of Figure 4, and the members C¹—C² of Figure 5 may function as true columns or load-supporting members, and the spacing thereof may be appropriately selected, if desired, with respect to the beams of the ceiling or roof structure; the just-identified members may, however, also function as beams where the wall structures are to be placed in horizontal position to form, for example, ceiling, flooring, roofing, or the like, particularly where the space OS is to be filled with concrete. In either case, it will be seen that the structures provide for wide flexibility of application and for a wide choice of materials to be associated with them. The members 17—18 may, as indicated above, comprise any appropriate building material, such as sheet metal, lathing, preferably metallic lathing, plaster, sheet materials like asbestos composition, fiber-board, so-called sheet-rock, plaster-board, maze-wood, sheet-stone, cement, tile, and the like.

Furthermore, it will be seen that the structural elements employed are capable of inexpensive and rapid fabrication and of rapid and inexpensive assembly in the course of erection. Also, it will be seen that the structures are of a thoroughly practical character and well adapted to meet the varying conditions of practical use.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

1. In building construction, in combination, a plurality of spaced structural supporting members having opposed edge faces respectively aligned along two spaced planes, said members carrying wall surfacing means aligned along said edge faces, said members having web-like means intermediate of the opposed edge faces thereof, each of said supporting members having on each side thereof and extending lengthwise means coacting with said web-like means and forming a longitudinally extending channel, and means of sheet-like material bridged across between adjacent supporting members and having its opposed edges received respectively in the channels of the two supporting members between which it extends thereby to divide the space between the planes of said opposed edge faces into two spaces, said channels holding said sheet-like means at the edges thereof to resist thrusts from either of the two spaces.

2. A construction as claimed in claim 1 in which the web-like means of the supporting members extends in the general direction of said sheet-like dividing means and in which the means forming said channels comprises arm-like extensions from said web-like means for connecting to the latter said edge faces, said arm-like extensions being at such angles as to form therebetween said channel.

3. A construction as claimed in claim 1 in which said web-like means extends in a plane generally at right angles to the general plane of said sheet-like means and has the channels formed in said web-like means.

4. A construction as claimed in claim 1 in which said channel forming means comprises sep-

arate members shaped to provide channels, and means securing said separate members respectively to the web-like means of said supporting members.

5. A construction as claimed in claim 1 in which the web-like means of said supporting members is in two parts, whereby each of said supporting members is a two-part member divided along a plane intermediate of the spaced planes of the opposed edge faces of said supporting members.

6. A construction as claimed in claim 1 in which the web-like means of said supporting members is in two parts, whereby each of said supporting members is a two-part member divided along a plane intermediate of the spaced planes of the opposed edge faces of said supporting members, adjacent portions of the two-part web-like means of each supporting member being provided with means for securing the two together.

7. A construction as claimed in claim 1 in which the web-like means of said supporting members is in two parts, whereby each of said supporting members is a two-part member divided along a plane intermediate of the spaced planes of the opposed edge faces of said supporting members, adjacent portions of the two-part web-like means of each supporting member being provided with interengageable portions for connecting and holding together the two parts of each supporting member.

8. A construction as claimed in claim 1 in which the web-like means of said supporting members is in two parts, whereby each of said supporting members is a two-part member divided along a plane intermediate of the spaced planes of the opposed edge faces of said supporting members, adjacent portions of the two-part web-like means of each supporting member being provided with complementary interengageable hook-shaped parts for connecting together the two parts of each supporting member.

9. A construction as claimed in claim 1 in which the web-like means of said supporting members is in two parts, whereby each of said supporting members is a two-part member divided along a plane intermediate of the spaced planes of the opposed edge faces of said supporting members, adjacent portions of the two-part web-like means of each supporting member being provided with complementary interengageable yieldable members for connecting together the two parts of each supporting member.

10. A construction as claimed in claim 1 in which the web-like means of said supporting members is in two parts, whereby each of said supporting members is a two-part member divided along a plane intermediate of the spaced planes of the opposed edge faces of said supporting members, adjacent portions of the two-part web-like means of each supporting member being provided with complementary recessed and headed members, the one receivable within the other, for connecting together the two parts of the supporting member.

11. A construction as claimed in claim 1 in which the web-like means of said supporting members is in two parts, whereby each of said supporting members is a two-part member divided along a plane intermediate of the spaced planes of the opposed edge faces of said supporting members, adjacent portions of the two-part web-like means of each supporting member being provided with complementary recessed and headed members, the one receivable within the other, for

connecting together the two parts of the supporting member, one of said complementary parts being resiliently yieldable to permit interengagement of one by the other upon the application of a certain force.

- 5 12. In building construction, in combination, a plurality of spaced structural supporting members having opposed edge means alined along two spaced planes for receiving and having secured thereto and respectively along said two spaced planes suitable wall surfacing means, said supporting members having extending therealong and intermediate of said two spaced planes means forming a longitudinally extending channel in each member and facing toward the next supporting member, thereby to present, for two successive spaced supporting members, a pair of longitudinally extending channels with their open

ends facing toward each other, and means of sheet-like material bridged across between adjacent supporting members and having its opposed edges received respectively in and supported by the two channels of said two members, the said channels holding said sheet-like means at the edges thereof to resist thrusts from either side of said sheet-like means.

10 13. A construction as claimed in claim 12 in which said means of sheet-like material is in several layers, one of which is sheet-like in form and made of a relatively strong and self-sustaining material and the other of which is made of a heat-insulating material relatively weak mechanically and receiving its mechanical support 15 from said first-mentioned layer.

BERNARD LONDON.
